UNIVERSAL FOLDER FOR SEWING MACHINES

Joseph Galkin, New York, N. Y., assignor to
Trouser Waist-Band Machine Co. Inc., New
York, N. Y., a corporation of New York

Application August 31, 1934, Serial No. 742,338

4 Claims. (Cl. 112—147)

This invention relates to a new and improved folder for sewing machines and more particularly to a folder which is adapted for applying waistbands to the waistband portion of trousers.

An object of this invention is to provide a folder which is adapted for applying waistbands consisting of a layer of lining material and an intermediate layer of stiffening fabric such as canvas in superimposed relation upon the waistband portion of trousers and cause said waistband to be affixed by machine stitching to the trousers without any folds in the stiffening fabric.

Another object of this invention is to provide a universal folder designed for applying straight waistbands as well as pleated waistbands to the waistband portion of trousers.

Another object of this invention is to provide a folder having a lower portion designed to receive the waistband fabrics from a supply reel positioned above the operating table of the sewing machine, the said fabrics entering said folder in a direction transverse to the line of stitching and being folded in an oblique direction and caused to leave an upper portion of said folder in a direction parallel with the line of stitching.

Another object of this invention is to position the outer marginal edge of the hemming section of the upper portion of the folder in angular relation with the line of stitching so as to prevent the formation of puckers in the lining material of the waistbands.

Another object of this invention is to provide a folder for applying ready made or pre-formed waistbands to trousers, the said folder being designed for the independent adjustment of the trousers fabric guiding means to permit variation of the width of trouser fabric which is to be inserted between the stiffening fabric and the lining material of the waistband.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a plan view of the folder mounted on the base-plate of a sewing machine.

Figure 2 is a front elevation of the folder.

Figure 3 is a side elevation of the folder.

Figure 4 is an enlarged sectional view of a plain waistband as completed on the machine.

Figure 5 is an enlarged sectional view of a pleated waistband as completed on the machine.

The folder 10, as illustrated, consists of a supporting-base 11 having slots 12 adapted to receive screws 13 for securing the folder to the base-plate 14 of a sewing machine. These slots are so disposed in the supporting-base 11 that the folder 10 may be shifted in a direction cross-wise of the line of seam formation to different set positions. Integral with the supporting-base 10 11 is an outwardly flaring angularly bent folding section 15 having a right-angular extension 16 positioned below the base-plate 14 of the sewing machine. The extension 16 comprises a fixed guiding slot 17 serving to receive one edge of a band of stiffening fabric 18 from a supply reel (not shown) but positioned above the operating table or base-plate 14 of the sewing machine. The supply reel carries a roll of ready made or pre-formed waistband material made of a layer 20 of lining and a stiffening layer of canvas stitched together lengthwise along one edge. A channel-shaped guideway 19 positioned parallel with the line of stitching has been formed on the extension 16 and serves to receive the rectangular portion of a slide arm 20 in close engagement. The slide arm 20 has a slot 21 to receive a screw 22 for securing the arm to the extension 16 in different set positions. A U-shaped guide 23 has been provided for guiding the stitched edge 30 of the pre-formed waistband material. The guide 23 is permanently united to a bar 24 fastened to the slide arm 20 by screws 25. The guide 23 may thus be shifted in a direction parallel with the guiding slot 17 to form between them a path of 35 adjustable width for the particular width of waistband desired. The width of the waistband to be formed is governed by the width of the stiffening fabric 18 shown in Figure 1.

A hemming section 26 has been permanently 40 united to the undersurface of the extension 16, below the guiding slot 17 in parallel relation with said guide. The hemming section 26 is substantially U-shaped and has a guiding member or tongue 27 centrally secured therein.

Mounted on the supporting-base 11 is a channel-shaped guideway 28 positioned transverse with the line of stitching and serves to receive the rectangular portion of a slide arm 29 in close engagement. The slide arm 29 has a slot 30 to 50 receive a screw 31 for securing the arm to the base 11 in different set positions. A U-shaped guide 32 has been provided for guiding the stitched edge of the pre-formed waistband material. The guide 32 is permanently united to 55

the slide arm 29. The guide 32 may thus be shifted in a direction parallel with the line of stitching of the sewing machine. A hemming section 33 has been formed from one end portion 5 of a plate 34 mounted above the supporting base 11 and secured to said base by means of an arm 35 and fastening means 36. The folding edge 37 of the hemming section 33 has been positioned in angular relation with the U-shaped 10 guiding member 32, forming a tapering passage-way between these members with the largest end of the taper terminating at the needle 38. The hemming section 33 is substantially U-shaped and has a guiding member or tongue centrally secured therein. The tongue 39 projects outwardly 15 from the hemming section 33 and slopes downwardly and terminates adjacent the needle 38 at a point 40.

An independent guide 41 for the edge of the trouser fabric has been positioned on the base-plate 14 of the sewing machine and is provided with an edge portion 42 which extends slightly upward. As shown in Figure 1, the guide 41 has slots 43 serving to receive screws 44 for securing said guide and the edge portion 42 thereof in various adjusted positions with relation to the folding edge 37 of the hemming section 38. The guide 41 may thus be adjusted on the base-plate 14 and this adjustment permits variation of the width of trouser fabric to be inserted between the stiffening fabric and the lining material of the waistband.

In operation, the roll of pre-formed waistband material 45 above the operating table or base-plate 14 of the sewing machine, is inserted in the lower folding and guiding section 46 with the stiffening fabric 18 facing up and with the free edge of the stiffening fabric in contact with the guiding slot 17; the stitched edge of lining material 47 and stiffening fabric 18 being in contact with the U-shaped guide 23. The waistband material is drawn through the lower folding and guiding section 46 and is folded in an oblique direction about the angularly bent section 15 and is inserted in the folding and guiding section on the supporting-base 11 with the lining material facing up and with the free edge of the stiffening fabric in contact with a guide channel 48 formed by an upturned edge 49 of the supporting-base 11. The stiffening fabric goes through unfolded. The free edge of the stiffening fabric leaves the guide channel 48 slightly to the right of the needle 38. The stitched edge of lining material 47 and stiffening fabric 18 contact with the U-shaped guide 32. The edge of the lining material comes out from the rear end of the angularly positioned hemming section 33 folded to the desired size or width of waistband and is immediately stitched adjacent the folded edge 60 and is drawn through the folder by a feed mechanism (not shown).

The object of the angular position of the hemmer section 33 is to cause the underfolded lining material to enter the hemming section 33 with a width less than the desired width of waistband and to leave the folder at the needle with the desired width so as to cause the lining fabric to be under tension and to lay taut on the stiffening fabric. There is a very narrow linear passage 70 between the tongue 39 and the inclined folding edge 37 of the hemmer section 33 which assists in maintaining the folded position of the lining fabric and also causes the lining material to be taut at the point of exit from the folder 75 and prevents the formation of puckers or folds.

in the lining material of the sewed waistband. Due to the fact that the lower fabric is somewhat stiff, it retains the lining in the guide 32.

It is essential to place the reel containing the pre-formed waistband material above the operating table of the sewing machine so as to keep it out of the way of the operator and also to prevent oil from dripping down on the said material if it were placed below the operating table. The - 11 - 5

The stitching mechanism of the sewing machine may be of any character but preferably of the type forming zigzag stitching which pass alternately through the folded edge of the lining and through the trouser and stiffening fabrics and then only through the trouser and stiffening fabrics 50 and 18, as shown in Figures 4 and 5. 10 15

I claim:

1. A folder for sewing machines designed for applying waistbands to trousers, comprising a supporting base member, a folding and guiding section for receiving a waistband which is composed of two strips stitched together along one edge, said section being positioned below said base and transverse to the line of stitching, a folding and guiding section positioned on said base and parallel with the line of stitching for receiving said waistband and an intermediate oblique folding section connecting said upper and lower sections into coaxing relationship, said intermediate section being designed to reverse the position of the strips composing said waistband 20 25 30

2. A folder for sewing machines designed for applying waistbands to trousers, comprising a supporting base member, a folding and guiding section for receiving a waistband which is composed of two strips stitched together along one edge, said section being positioned below said base and transverse to the line of stitching, a folding and guiding section positioned on said base and parallel with the line of stitching for receiving said waistband, an independent guide for the edge of the trouser fabric and means for supporting said independent guide whereby it may be adjusted to permit variation of the width of trouser fabric inserted between the layers of the waistband. 35 40 45

3. A folder for sewing machines designed for applying waistbands to trousers, comprising a supporting base member, a folding and guiding section for receiving a waistband which is composed of two strips stitched together along one edge, said section being positioned below said base and transverse to the line of stitching, a folding and guiding section positioned on said base and parallel with the line of stitching for receiving said waistband and an intermediate oblique folding section connecting said upper and lower sections into coacting relationship, said folding member on said base being angularly positioned with relation to the guiding member on said base and forming a tapering passageway for the lining material with the largest end of the taper terminating at the needle and causing the lining layer of said waistband to lay taut in waistband making relationship. 50 55 60 65 70 75

4. A folder for sewing machines designed for applying waistbands to trousers, comprising a supporting base member, a folding and guiding section for receiving a waistband which is composed of two strips stitched together along one edge, said section being positioned below said base and transverse to the line of stitching, a folding and guiding section positioned on said base and parallel with the line of stitching for receiving 70
75

said waistband and an intermediate oblique folding section connecting said upper and lower sections into coacting relationship, said folding member on said base being angularly positioned with relation to the guiding member on said base and forming a tapering passageway for the lining

material with the largest end of the taper terminating at the needle and causing the lining layer of said waistband to lay taut in waistband making relationship, and an independent guide for the edge of the trouser fabric.

JOSEPH GALKIN.
